PROTECTING DEVICE FOR ARMATURE SHAFTS

Rudolph E. Pesek, Berwyn, and Charles J. Pesek,
Brookfield, Ill.

Application June 30, 1953, Serial No. 365,137

5 Claims. (Cl. 118—503)

This invention is directed to portable devices or racks adapted for mounting a plurality of mechanical or structural parts of devices during the course of manufacture and for temporarily protecting projecting parts of the manufactured articles during the application of any one of a variety of coatings or during the subjection of such manufactured articles to either liquid or vaporous materials. Our devices are adapted for use in connection with protection of parts of the articles regardless of whether the liquid or vaporous material is applied by immersion, by spraying, brushing or other manual application.

It is an important object of our invention to provide portable devices of the described class adapted to hold manufactured articles in a releasable means and so that certain parts of the article will be sealed and protected against contact with the liquid or vaporous material while it is being applied to the remainder of the manufactured articles, and it is a further object, by protecting certain parts from such applied material, to eliminate the labor and time of subsequently removing the applied material from the parts protected by our device.

A further object of our invention is the provision of portable racks or holding devices adapted for mounting a plurality of shaft-bearing armatures or the like during application by immersion to the major portion of the armatures of liquified materials such as resin, lacquer, or the like, the function of such liquid material, when later cooled and solidified, being to protect the wiring of the armature or other electric device against moisture, oxidation and deterioration.

A further object of our invention is the provision of portable racking devices having a plurality of upwardly extending holding members in the lower part thereof and into which holding members a plurality of projecting shaft end portions are adapted to be mounted by gravity so that a temporary seal is effected between the upper ends of said holding members and portions of the main body of the armature so that upon immersion into a liquified coating material, the portions of the armatures within said holding members will not be subjected to contact with the liquified material; said devices also having means for releasably impinging the armatures in sealed position with respect to said holding members.

Other and further objects of our invention will be apparent from the following description and appended claims.

This invention in a preferred form is illustrated and described with particular reference to the armatures of electric motors, though it is to be understood that other manufactured structural parts having projecting portions to be protected from a liquid material upon immersion, may be satisfactorily mounted and held in desired position during process of either submersion in a liquid material or in another form of application of either liquid or vaporous material to the exposed parts of the articles.

On the drawings:

Fig. 1 is an elevational view of our device and with cer-

tain parts in cross section and with the same mounted on a typical tank or receptacle and illustrating two armatures in position.

Fig. 2 is an enlarged cross section view of one of the upwardly extending shaft end members and a fragment of the lower casing, housing or base in which said holders are mounted.

Fig. 3 is a perspective view of our device and without any manufactured articles mounted on the holding members thereof.

As shown on the drawings:

Referring to Fig. 1, numeral 10 designates an elongated casing, housing or enclosed base defined by bottom and side walls and by a substantially elongated upper wall

15 11 in which a plurality of spaced apart openings or apertures are formed. Said mounting base or casing 10 is preferably relatively long and shallow, though its depth and proportion may vary according to the type and size of the projecting portions of manufactured articles to be mounted with respect to same. One of the purposes of said mounting base which forms a relatively rigid portion of our portable rack is to provide a completely enclosed and sealable space or chamber in which the lower end portions of the articles to be partially protected and shielded from a liquid or vaporous bath may project.

Reference numeral 12 designates a metal vent pipe whose lower end portion is suitably secured, for example by welding in an aperture 13 formed preferably in the intermediate portion of the upper wall 11. Said vent pipe 12 extends upwardly a sufficient distance so that its opening will be well above the surface of any liquid bath into which the device is placed. Said vent or breather pipe 12 allows expanding heated air to escape from within the chamber of the casing 10, both during immersion and 35 during the subsequent baking which hardens the resin. Such escape of air prevents breaking of the seal between tape 21 and sleeves 18.

Numerals 14 designate a pair of suspension and connecting metal rods whose lower ends are suitably secured, for example, by threading engagement in the opposite ends respectively of the upper metal wall 11. The upper ends of said rods or bolts 14 are threaded and are adapted to be relatively mounted in suitably spaced openings in an elongated metal cross bar 15, said releasable securance 45 being preferably by means of a pair of wing nuts 16 as illustrated in Fig. 1.

Washers or stop lugs 17 illustrated in Fig. 1 are preferably mounted on the upper ends of the connecting rods 14 in fixed and secured positions at the lower end of the 50 upper threaded portions of rods 14 so that the same act as a stopping or limiting means against the further descent of the cross bar 15. This permits the wing nut 16 to be tightened by hand and so that the same will be under tension, the said stop washers 17 forming the resisting elements against further movement of cross bar 15 in a normally downwardly direction. I desire it to be understood that other equivalent releasable fastening elements may be utilized in substitution of the wing nuts 16 and the threads on the rods 14 to releasably mount the 55 carrying and cross bar 15 with respect to the upper portions of the connecting rods or bolts 14.

The cross bar 15 is preferably made of flat metal straps or bands and of a length substantially longer than the length of the base 10, said length also being such that 60 the opposite projecting ends may be rested upon and supported by either the side walls or the end walls of a tank or receptacle which is adapted to contain the proper depth of liquid material to which the manufactured articles are to be subjected either by immersion or other manual application.

70 A plurality of metal sleeve-like or tube-like mounting and holding means 18 are mounted in longitudinal spaced

positions in spaced apart holes formed in the upper wall 11 of the base or housing 10 and these are secured in perpendicular and normally upwardly extending position by either welding as indicated at 19 or optionally by threading engagement with side wall 11. The distance between the respective holding members 18 may vary in a wide range and be of such distance to provide ample clearance and spacing between the projecting and exposed parts of the armatures or other mechanical articles or structures which have an enlarged body portion and a projecting reduced portion. In other words, the smaller the maximum dimension of the manufactured articles, the closer the respective holding members 18 may be mounted so that more of such articles may be treated or coated in a holding rack or with a base of a given size.

The upper end portions of the holding members 18 are exteriorly beveled to provide a substantially sharp annular edge 20 on each thereof, and so that the inner circumferential face of said holding members extends straight downwardly from the relatively sharp annular edges as illustrated in Fig. 2. In the manufacture of armatures for electric motors and generators the metal shafts of the desired length and diameter have first applied to their intermediate portions (for a distance slightly longer than the combined length of the armature body and the commutator segments) a suitable insulating tape 21 which is spirally wound about the intermediate portions of such armatures so that such tape will provide an insulation between the inner subsequently wound wires and the shaft. The insulating tape 21 is wound on such armatures so that a small part of the endmost convolution of such tape will be exposed beyond the end portion of the body of the armature, as illustrated in Figs. 1 and 2. The inside diameters of the holding members 18 may be substantially the same, though very slightly greater than the diameters of the shafts or projecting parts of the armatures or mechanical structures to be mounted so that the projecting parts to be protected during the application of a liquid material will fit substantially snugly into the holding members 18, though with sufficient clearance to permit insertion and withdrawal of the armatures by hand.

The armatures illustrated in Fig. 1 are designated by numeral 22 and their respective shafts or axles by numeral 23. The lower portions of the shafts 23 which are insertable into the holding members 18 are designated as 23a and the end portions of the latter usually are either threaded or grooved for the convenient mounting of either pulleys, gears or the like.

It has been found that the application of either a liquid resin or other protecting coating to the projecting portions of the shafts 23a, simultaneously with the application of such protecting coating to the wires of the armatures themselves, necessitates the laborious and time-consuming work of subsequently removing the hardened resin coating or other hardened protecting material from one projecting end portion of shaft edge armature.

When those projecting portions of the armature shaft which are opposite the commutator-carrying portion are inserted and allowed to rest by gravity in the respective bevelled holders 18, the annular bevelled edges 20 will slip partially under the edge of the projecting part of the insulating tape 21 in the manner illustrated in Fig. 2 and so that a temporary seal is formed between the bevelled edges 20 of holders 18 and the tape 21 on each of said armatures, this preventing the entry of the liquid resin or other liquid coating or treating material which may compose the bath or liquid mass into which the armatures are partially submerged.

Said armatures 22 are mounted in said holders in the described manner while the cross bar 15 is removed. After an armature has been mounted in said manner in each of the respective holders 18, the cross bar is mounted upon the connecting rods 14 and the nuts 16 are screwed tight on the threaded ends of rods 14 and thereupon the

rack and the mounted armatures are ready for immersion or for other manual application of the liquid material to the exposed parts of the armatures or to desired portions thereof.

- 5 In the manufacture of armatures, it is desirable that the relatively hot liquid resin or equivalent moisture-resistant material be applied to the wires of the armature and accordingly the vertically positioned armatures mounted in the manner described and with the cross bars 15 preferably impinging upon the upper end of the armature shafts 23, be immersed in the hot resin bath only to a depth so that the hot liquid resin will run into the spaces between the wires of the armatures and coat itself upon such wires and so that such resin material will not contact the commutator bars or segments or the uppermost ends of the shafts 23. After the armature bodies have been immersed for a short time in a body of said liquid resin or other protective coating material which is of the type adapted to harden in normal room temperatures, 10 the entire rack is withdrawn from the body of the liquid material and the surplus liquid material allowed to drip off, and in normal practice, the said racks holding said armatures or parts are mounted on suitable brackets of an oven and then baked until the resin will harden upon 15 the wires and the armature body to form a firm moisture-resistant and insulating coating thereon.

The individual armatures may be withdrawn by hand from the holding members 18 either as soon as the rack has been withdrawn from the oven or after the resin 20 has partially or fully hardened.

It will be understood that the said rack and holding members may be repeatedly reloaded with either armatures or with other structural parts which have rounded projecting portions extending from a major body portion 35 so that when the projecting portion is inserted into the holding members 18, a temporary seal will be provided between the bevelled ends 20 of member 18 and the major body portion of the article and so that the liquid coating or protecting material will be thereby prevented from 40 contacting the projecting reduced portions within the holding members 18.

In instances where the armatures or other articles mounted in the rack as aforesaid are immersed into a relatively hot bath, the transfer of heat from the bath through the walls of the base or casing 10 will heat the air within said casing 10 to cause its expansion. Therefore, it is advisable to provide a means for permitting the escape of a portion of such heated air so that such expanded heated air will not force itself upwardly through 45 the respective holding members 18 and through the spaces between said holding members and the shaft portions 23a and through the seal between the upper bevelled end portions of said holding members and either the tape 21 or the enlarged body portion of the article in instances where 50 no such projecting tape is present. The forced escape of heated air through the temporary seal would cause a leakage and entry of part of the liquid coating and protecting material through such temporary seal, and this is prevented by the provision of an air vent means exemplified by the vent pipe 12 which extends upwardly a 55 sufficient distance to always have its outlet above the mass of heated liquid material into which the rack and its held articles are immersed.

We desire it to be understood that our novel rack and holding means may be satisfactorily used for temporarily shielding and protecting the projecting portions of various manufactured and merchandise articles other than armatures and also in instances where the liquid material to be applied to the exposed parts of such manufactured articles 60 is applied in the form of a spray, for example a spray gun from which lacquer, paint, enamel or other protecting and treating material is to be applied to the exposed parts of the manufactured articles.

The use of our novel holding and protecting means 65 such as described in the aforesaid example saves a con-

siderable amount of labor and costs which have otherwise been necessary in the usual dipping of armatures and other articles into a liquid type of coating and protecting material and which necessarily must be subsequently removed from portions of the shaft of the armatures or from portions of the manufactured articles which require contact and remounting with other structural and mechanical parts.

As many changes could be made in the above construction, and as many apparently widely different embodiments of my invention within the scope of the claims could be constructed without departing from the spirit and scope thereof, it is intended that all matter contained in the accompanying specification shall be interpreted as illustrative and not in a limiting sense.

I claim:

1. In a device for protecting projecting parts of mechanical structures during applications of coatings to portions of such structures; an elongated apertured cross bar; an elongated base comprising a housing having closed ends and having a plurality of upwardly opening apertures therein; a plurality of upwardly extending connecting bars having their lower ends connected to said base, the upper ends of said connecting bars being threaded and removably mounted in apertures of said cross bar; a plurality of metal cylindrical tube-like holders mounted in said base and spaced longitudinally thereof, said holders being exteriorly bevelled at their upper ends to present relatively sharp annular edges, said holders being adapted to receive the projecting portions of mechanical structures which are to be protected during application of protective coatings to the remaining and exposed parts of said mechanical structures, said bevelled upper edges of said holders being adapted to engage and form a seal with the normally exposed parts of said mechanical structures.

2. In a portable device for protecting the projecting portions of shafts of armatures or the like during the step of immersion of such armatures in a body of hot liquified moisture resistant material; an elongated casing having a substantially flat upper wall; an upwardly extending bent pipe mounted in said upper wall and being of a length to extend above a receptacle into which said device is positioned; a plurality of cylindrical mounting members mounted in spaced apart relation in said upper casing wall; each of said mounting members having its upper end bevelled; the bevelled portions of each of said mounting members being adapted to have the projecting end portion of an armature shaft mounted therein to provide a seal with said armature shafts; an elongated cross bar having projecting ends adapted to be positioned on stationary objects during the immersion of said armature; and a plurality of connecting rods secured at their lower ends to said casing and having manually removable connection means on their upper ends adapted to releasably connect said rods to said cross bar, said vent pipe having an upper portion extending above the top of a receptacle into which said device is immersed to permit escape of air from within said casing.

3. In a portable device for protecting the projecting portions of mechanical articles during the step of applying liquid compositions to portions of said articles; an elongated base comprising a closed housing and having a substantially flat upper face; a plurality of cylindrical mounting members mounted in spaced apart relation in said upper face of said base; each of said mounting members having its upper end of annular shape; each of said mounting members being adapted to have the projecting end portions of a mechanical article mounted therein

whereby the upper end portion of each of said mounting members will engage and form a temporary seal with the larger portion of the mechanical article to thereby protect the inserted portion of such article from contact

5 with a liquified material during application of said liquid material to the exposed portion; an elongated cross bar having projecting ends adapted to be positioned on stationary objects during the application of said liquid material; and a plurality of connecting rods secured at their lower ends to said base and having manually removable connection means on their upper ends adapted to releasably connect said rods to said cross bar.

10 4. In a device for protecting projecting parts of mechanical structures during applications of coatings or liquid materials to portions of such structures; an elongated apertured cross bar; an elongated housing providing a base and having closed ends and having a plurality of upwardly opening apertures therein; a plurality of upwardly extending connecting bars having their lower ends 15 connected to said base, the upper ends of said connecting bars being removably connected to said cross bar; a plurality of metal cylindrical tube-like holders mounted in said base and spaced longitudinally thereof, said holders being bevelled at their upper ends, said holders being 20 adapted to receive the projecting portions of mechanical structures which are to be protected during application of protective coatings or materials to the remaining and exposed parts of said mechanical structures, said bevelled upper edges of said holders being adapted to engage and 25 form a seal with the normally exposed parts of said mechanical structures.

30 5. In a device for protecting the projecting portions of mechanical structures which include an enlarged body portion; an elongated hollow metal housing having an 35 apertured substantially flat upper wall; an upwardly extending air vent pipe communicatively connected to said upper wall of said container and being of a length to extend above the top of a receptacle into which said device is positioned, an apertured elongated metal cross 40 bar having its opposite ends projecting outwardly and adapted to be positioned upon the opposite portions of a receptacle or the like; upwardly extending connecting rods secured to the upper wall of said container and being removably connected to said cross bar; a plurality of 45 upwardly extending spaced apart tube-like article holders securely mounted in the upper wall of said container and extending upwardly a sufficient distance to form a protective enclosure for projected parts of the mechanical structures to be partially coated, said holders being 50 adapted to protect said projecting portions against a liquified coating and being adapted to form a temporary seal at the areas of engagement thereof with the enlarged portions of said mechanical structures; said cross bar and connected container and holders providing for immersion 55 of a plurality of mechanical parts partially mounted in said holders and into a body of liquified coating material within a tank.
